Primary Examiner — Ralf Seifert(74) *Attorney, Agent, or Firm* — Fenwick & West LLP(57) **CLAIM**

We claim the ornamental design for an automatic electronic air pump, as shown and described.

DESCRIPTION

FIG. 1 is a front and right perspective view of an automatic electronic air pump showing our new design;

FIG. 2 is a right view thereof;

FIG. 3 is a front view thereof;

FIG. 4 is a front and right perspective view of a second embodiment of an automatic electronic air pump showing our new design;

FIG. 5 is a right view of FIG. 4; and,

FIG. 6 is a front view of FIG. 4.

The left views of the first and second embodiments are mirror images of the right views.

The top of the automatic electronic air pump is flat and devoid of surface ornamentation in the first and second embodiments.
